Designs No. 1 and 2 show square versions of an IoT module respectively with or without pads arrangements in the lower part of the module center; designs No. 3 and 4 show rectangular versions of an IoT module respectively with or without pads arrangements in the lower part of the module center; designs No. 5 and No. 6 show scaled versions of an IoT module respectively with or without pads arrangements in the lower part of the module center. The dashed broken lines illustrate portions of the article, and form no part of the claimed design.
